[57] CLAIM

The ornamental design for an edging tool, as shown.

DESCRIPTION

FIG. 1 is a front elevational view of a garden tool showing my new design;

FIG. 2 is an enlarged front elevational view thereof;

FIG. 3 is a bottom plan view thereof;

FIG. 4 is a top plan view thereof;
FIG. 5 is a side view thereof, the opposite side of the tool being a mirror image; and

FIG. 6 is an elevational view of the side opposite to that shown in FIG. 2.

The handle represented in broken lines is for illustrative purposes only.
